(57) **CLAIM**

The ornamental design for a bowl as shown and described.

DESCRIPTION

1. Bowl

1 : Perspective

This design is related to a bowl having a stem; the bowl is essentially cylindrical in form, with a uniform continuation from the base to the rim; the outer surface of the bowl is decorated with an all-round geometric pattern of three rows

(Continued)

of three parallel rows, resembling drops or leaves; the diameter of the stem is smaller than the diameter of the bowl.

1 Claim, 1 Drawing Sheet
